United States Patent Office

Des. 208,765
Patented Oct. 3, 1967

208,765

AIRPORT BUILDING

Samuel J. Solomon, 9101 Colesville Road, Silver Spring, Md. 20910, and John S. Samperton, Sumner, and William Procopiow, Bethesda, Md., said Samperton and said Procopiow assignors to said Solomon

Filed Feb. 6, 1967, Ser. No. 5,708

Term of patent 14 years

(Cl. D13—1)

Fig. 1.

FIG. 1 is a top plan view of an airport building, showing our new design;

FIG. 2 is an enlarged elevational view, looking in the direction of the arrows 2—2 in FIG. 1;

FIG. 3 is an enlarged side elevational view, looking in the direction of the arrows 3—3 in FIG. 1;

FIG. 4 is an enlarged side elevational view, looking in the direction of the arrows 4—4 in FIG. 3; and

FIG. 5 is an enlarged side elevational view, looking in the direction of the arrows 5—5 in FIG. 2.

We claim:

The ornamental design for an airport building, as shown.
